UNITED STATES PATENT OFFICE.

SIMON MACKAY, OF ATHOL, MASSACHUSETTS, ASSIGNEE TO UNION TWIST DRILL COMPANY, OF ATHOL, MASSACHUSETTS, A CORPORATION OF MASSACHUSETTS.

GRINDING-MACHINE.

1,052,605.

Specification of Letters Patent. Patented Feb. 11, 1913.

Application filed July 26, 1910. Serial No. 574,845.

To all whom it may concern:

Be it known that I, SIMON MACKAY, a citizen of the United States, residing at Athol, county of Worcester, Commonwealth of Massachusetts, have invented certain new and useful Improvements in Grinding-Machines, of which the following is a specification.

This invention relates to the positioning 10 of a milling cutter in the grinding machine in which it is to be sharpened, and particularly to a peripheral tooth position indicator for the same.

In the patent to Rivett, No. 690999, the 15 cutter tooth is peripherally gaged by a fixed stop. In my present invention I have sought to overcome certain practical difficulties attendant upon the use of such a stop or pawl, while preserving and increasing 20 the essential advantages which are secured by this manner of gaging.

The rearward relief of the outside face 25 of the cutter teeth forms an incline of comparatively slight eccentricity to the axis of rotation of the cutter, and yet it is sufficient to materially decrease the effective length of the tool upon a very slight grinding. In order to accurately gage a tooth peripherally it is, therefore, necessary that the contacting member be capable of accurately determining 30 the proper radial distance desired in order that the ground face of the cutter when sharpened shall be exactly in the plane sought. On account of the comparatively slight eccentricity of the rearward tooth relief a fixed stop is apt to jam 35 on the incline of the outer cutter edge, permitting a variation in the adjustment of the cutter.

In my present invention I have devised a 40 movable indicator which is incapable of jamming and which provides for the utmost nicety of adjustment. In order, moreover, to secure the full benefit of such a gaging 45 as has been suggested, it is necessary that the cutter tooth be advanced to the grinding disk on a true radial line. It will be clear from a consideration of such a structure as that of Rivett that a slight variation 50 in the grind or grinder will be so accentuated at the point of the tooth as to offset that delicacy of adjustment which is sought in the peripheral gaging.

My invention, therefore, consists further 55 in the provision of means for so manipulat-

ing the work and the abrasive wheel that the cut will be accomplished on a true radius which, together with the peripheral gaging, assures the uniformity of tooth length which is sought.

The construction and operation of my device will be more fully described in the specification which follows. In that specification, and in the drawings which form a part of it, I have shown, as illustrative of my device, an embodiment which I find satisfactory in practical use.

Throughout specification and drawings like reference numerals are employed to indicate corresponding parts and in the drawings:—Figure 1 is a view of a grinding machine equipped with my invention, Fig. 2 is a plan view partly in section, and Fig. 3 is a detail showing the relative positioning of tooth grinding disk and gage arm.

The machine pedestal 1 is provided with a lateral bracket 2 on which there is a bed 3 supporting a slide 4 controlled by the milled knob 5.

6 is a cross slide, also controlled by a knob 30 7, and on this is supported in suitable bearings 8 a spindle 9 upon the end of which is mounted an abrasive wheel 10. The wheel 10 is covered by a hood 11 which is open on one side and adjacent to this opening is a work supporting slide 12 movably mounted 70 on a bracket 13 and controlled by a milled knob 14.

15 is a plate adjustable on the slide 12 by a set screw 16 which passes through a slot 90 on the plate. Near the end of the plate is a screw stud 17 upon which is centered a cutter, as indicated at X. Just in advance of the cutter centering stud 17 is pivotally mounted a gaging lever 18 which, at its forward end, is formed with a tooth engaging point 18¹ and at its rearward end 18² engages the actuating rod 19 of a spring multiplying indicator 20. Power is applied to the machine through a pulley 21 fixed on a 100 disk spindle 9.

The operation of my device is as follows: It is supposed that the emery wheel 10 has been properly trued off on its front face and is in condition to accurately grind the face of a tooth. A suitable plate 15 is selected which has a stud 17 of the right diameter to fit the cutter to be sharpened and with the cutter clamped on the stud the plate 15 is so adjusted that the 110

teeth of the cutter, when in contact with the gaged lever 18, will move the lever slightly away from a stop pin 18¹ which is set in the forward end of the slide. The 5 plate 15 is then clamped through the thumb screw 16. The emery wheel 10 is then adjusted by the milled knob 7 so that it will come to the bottom of the tooth α of the cutter X when the slide 12 is moved forward to the limit of its motion. With the 10 emery wheel 10 at rest the face of the tooth α is brought into contact with the wheel and the cutter is clamped upon the plate 15 by the screw 17. It is preferable that the 15 indicator 20 be adjustable, so as to bring the dial until the pointer reads on zero. The screw is then loosened slightly to release the cutter X on the plate and with the slide 13 drawn back the cutter is rotated to the right 20 until the indicator pointer shows a movement of from one to two thousandths of an inch, which is usually the amount of grinding desired. The cutter is then clamped by taking the screw 17 and the indicator dial 25 is brought again to zero. With the emery wheel drawn back by turning the knob 5 so that it will clear the cutter tooth the knob 14 is turned to move the slide 13 back and forth past the face of the emery wheel and 30 the emery wheel is itself advanced by successive slight turns on the knob 5 until the proper amount, that is, one or two thousandths, has been removed from the face of the tooth. The slide 13 is then drawn back 35 and the cutter loosened and turned until the indicator reads on zero with the end 18¹ of the lever 18 in contact with the next tooth which is then ground in the same manner as that just described. In this way it will 40 be seen that each tooth is ground with absolute accuracy on substantially a radial line and each tooth will have an absolute uniform length.

Various modifications may obviously be 45 made in the structure and operation of my

device, all without departing from the spirit of my invention if within the limits of the appended claims.

What I, therefore, claim and desire to secure by Letters Patent is:—

1. In a grinding machine for milling cutters, an abrasive wheel, means for moving said wheel longitudinally and transversely, a work support mounted for transverse movement relative thereto, means for adjustably centering a toothed cutter on said support and means for gaging on the outer face of a tooth the relative adjustment of the face of the tooth to the abrasive wheel.

2. In a grinding machine for milling cutters, an abrasive wheel, means for moving said wheel longitudinally and laterally, a work-support laterally movable with reference to said wheel, means for adjustably centering a cutter on said support and a pivoted indicator lever having one end adapted to engage the outside face of the cutter teeth and an indicator on the opposite end of said lever.

3. In a grinding machine for milling cutters, a frame, a longitudinal slide thereon, a transverse slide on said longitudinal slide, a longitudinal spindle on said transverse slide, an abrasive wheel on said spindle, a work-support on said frame and movably mounted with reference to said abrasive wheel, means for adjustably centering a cutter on said work support and a pivoted indicator lever on said slide and having one end adapted to engage the outside face of the cutter teeth and an indicator carried by said slide and operatively associated with the opposite end of said lever.

In testimony whereof I affix my signature in presence of two witnesses.

SIMON MACKAY.
